OIL BURNER

Filed Nov. 10, 1924

Fig. 1.

UNITED STATES PATENT OFFICE

FRANKLIN HARDINGE, OF CHICAGO, ILLINOIS, ASSIGNOR TO HARDINGE BROTHERS, INC., OF CHICAGO, ILLINOIS, A CORPORATION OF ILLINOIS

OIL BURNER

Application filed November 10, 1924. Serial No. 748,862.

My invention relates to improvements in oil burners, and especially to improvements in that type of oil burner wherein a rotary tubular atomizing nozzle, the inner surface 5 of which is in the shape of an inverted bell, is employed, and the oil passes upwardly over the inner surface to be discharged from its upper flared edge by centrifugal force where it is atomized and mixed with the air. My 10 invention is particularly concerned with improved means for feeding the fuel oil from a stationary supply conduit to the inner surface of the nozzle in such a manner that even with a very small consumption of oil per hour, 15 the flow will be continuous and uniform, at the same time being adapted for a considerable range of consumption.

Such a stationary conduit is preferably in the form of a stationary standpipe extending 20 into the interior of the nozzle, where its end is exposed to the heat of the flame within the fire box. Another object of my invention, therefore, is the provision of a cap or tip for the standpipe which will be so shielded and 25 cooled as to lessen the tendency of carbon deposits or the like on the standpipe, especially about its discharge opening. While in some types of burners the standpipe tip or cap may be easily removed for cleaning, these carbon 30 deposits are a source of trouble and annoyance and necessitate the shutting down of the burner for cleaning. By my invention, such carbon deposits are avoided in part by passing the oil through a passage within the cap 35 sufficiently close to the heated area to absorb the heat therefrom and thus act as a circulating cooling agent, and in part by flowing the oil over the exposed surface of the cap to cool it.

40 It has been found desirable to pass a current of air through the central passage of such a rotary atomizer not only to augment the supply of oxygen to the vaporized oil, but to flow out of the nozzle over the film of oil to help cool the nozzle at its open end where it is subjected to the intense heat of the flame, thus preventing a premature burning of the oil and preventing carbon deposits on the inner surface of the nozzle which would 45 50 impede the uniform flow of the oil film.

When a stationary standpipe is employed within the opening of the nozzle, it is most convenient to introduce this current of air at the lower end of the nozzle and lead it through a passageway between the standpipe 55 and the inner surfaces of the nozzle. As a further object of my invention, I provide a discharge tip or cap for the standpipe which permits a relatively free passage of such air past the cap in such a manner as not to interfere with continuity of oil delivery from the standpipe to the nozzle. I also contemplate the use of a standpipe comprising radiating portions in the path of this air current, which aid in the cooling of the head. 60 65

A still further object is to prevent the cap from being injured or the standpipe from being "sprung" out of adjustment with the rotating parts as has frequently resulted in the past from the use of a poker or other 70 carbon cleaning instrument inserted into the throat of the atomizer.

The foregoing, and further objects and features of my invention are set forth in the following description of a specific embodiment thereof, which is illustrated by the accompanying drawings, wherein 75

Figure 1 is a vertical longitudinal section through a portion of an oil burner;

Figure 2 is an enlarged detail in section of 80 the standpipe cap and associated parts;

Figure 3 is a plan view of the parts of Figure 2;

Figures 4 and 5 are a vertical section and plan of a modified form of standpipe cap; 85 and

Figures 6 and 7 are a vertical section and plan of another modified form of standpipe cap.

The oil burner I have shown in the drawings is of substantially the same type of construction as that shown in my co-pending application Serial No. 572,455, filed July 3, 1922, which discloses somewhat in detail the entire device. In order to clarify the drawings in this application, I have omitted a 90 95 number of elements and details.

Referring to the accompanying drawings, I have shown a head or housing 10 within which is vertically journaled a hollow spin- 100

dle 11 by the upper and lower ball bearings 12, and driven through a bevel pinion 13 and bevel gear 14 by a drive shaft 15 connected to a suitable source of power such as an electric motor. A hollow atomizing nozzle 16 is screw-threaded onto or otherwise rigidly secured to the upper end of the spindle 11 to rotate therewith. The lower portion of the nozzle 16 is tubular in form, its inner surface tapering very slightly toward its lower end, while the upper end of the nozzle is flared outwardly in a bell-like manner almost to a tangent with the horizontal plane of its upper edge. The upper periphery of the bell forms a knife edge 17, from which fuel oil is centrifugally discharged in a very thin film which is immediately atomized into a combustible mixture, which is thrown toward the annular wall 18 of the fire box. Immediately beneath its peripheral edge 17, the nozzle 16 carries a number of radial fan blades 19 which serve to force air outwardly against a deflector ring 20 to supply the air which is mixed with the atomized oil. An auxiliary air supply may also be had through the ports 21 beneath the outer edge of the deflector ring 20.

The oil which is discharged from the nozzle is forced by gravity or by pump, not shown, past a rotary metering valve, not shown, or the feed control valve 22, here shown, through a supply pipe 23, to the lower end of a standpipe 24 rigidly secured by a pedestal 25 to the base 26 of the device. The standpipe, which, of course, remains stationary and fixed to the pedestal 25, extends centrally through the hollow spindle 11 and into the lower end of the nozzle 16. A second tube 11' is disposed between the rotary spindle 11 and the standpipe 24 and supported at its lower end in the head 10. The tube 11' is spaced from the rotary spindle 11 to prevent friction and also spaced from the standpipe 24 to form an annular passage between the tube and standpipe as indicated at 24', this passage being open at the bottom of the head whereby air can flow upwardly to the interior of the atomizing nozzle 16. The upper end of the standpipe 24 is externally threaded as at 27 to receive the internally threaded end of the downwardly extending stem 28 of the standpipe tip or cap 29. The cap is formed with an enlarged head having a substantially cylindrical conformation shouldered outwardly at 30 adjacent its lower end to provide a narrow cylindrical discharge surface 31. Three obliquely bored radial ducts 29' lead from the interior bore of the cap to the outer side of the head, whereby the oil may flow downwardly onto the distributing shoulder 30 and thence to the discharge surface 31.

The upper end of the spindle 11, which carries the screw threads 32 by means of which the nozzle 16 is secured to the spindle, is projected upwardly above the threads and termi-

nates opposite the discharge surface 31 approximately mid-way between its upper and lower edges. This in effect forms a shoulder 33 for the lower end of the nozzle. The discharge surface 31 of the standpipe head is of sufficient diameter to leave a gap of capillary dimension which is only 1/64 of an inch or so between it and the inner edge of the spindle. Oil flowing from the standpipe onto its discharge surface 31 tends, because of its inherent body, to bridge the small air gap onto the rotary spindle by capillary action.

The high speed of the rotary spindle causes sufficient centrifugal force on the oil delivered to the shoulder 33 to cause it to move outwardly to the inner wall of the nozzle and to travel upwardly along this nozzle due to the slight outward taper of the lower end of the nozzle. Because of the inherent cohesion of the fuel oil, the oil at the upper inner edge of the spindle and also on the shoulder 33 will tend to rotate the oil still on the stationary discharge surface 31 of the standpipe. This not only aids in bringing the oil across the gap in a uniform feed, but also in turn tends to impart a rotary action to the oil as soon as it flows from the radial ducts 29' onto the shoulder 30. The shoulder 30, as well as the discharge surface 31, thus functions as a distributing surface so that the oil is evenly distributed around the periphery of the discharge surface before it is carried across to the rotary nozzle.

It is to be noted that in my oil delivery means there is no tendency for the oil which has been delivered to the rotary nozzle to be "whipped", as would be the case if there were oil feed tubes or other protuberances projecting from the standpipe to the nozzle and thereby impair the uniform feed of fuel oil from the nozzle edge by starting it up the tapered wall of the nozzle in spasmodic surges.

As the oil climbs the tapering inner wall of the nozzle under centrifugal force, it tends to further distribute itself as an even film which becomes thinner as it nears the top of the rotary nozzle and the flare of the nozzle increases. When finally discharged from the knife-edge 17, the film is so thin that it is readily atomized into the air discharged by the fan blades 19.

At its upper end, the spindle 11 carries a thimble 35 of somewhat lesser diameter, the thimble extending upwardly preferably into the cut away portion 36 of the standpipe cap beneath the apron 30 and downwardly within the upper edge of the tube 11'. This leaves an annular pocket 37 in the lower end of the nozzle 16. When the operation of the device is stopped, as by shutting off the motor, the film of oil on the inner surface of the nozzle will gravitate into this pocket 37, as will also the oil discharged from the standpipe as the pump comes to rest. Were it not for the

pocket 37, the oil would flow down the spindle and either dilute the lubricating oil for the bearings and gearing within the head 10, or be discharged into the open pan of the base 26. 5 The upper end of the spindle, which forms the outer wall for the pocket 37, is tapered slightly upwardly and outwardly so that the pocket will quickly empty itself of oil by centrifugal force when the device is again set in 10 operation. In addition to this, when the burner is in operation and the nozzle rotating at its usual high speed, any oil which is not immediately carried onto the shoulder 33 and tends to gravitate along the outer wall of the 15 pocket, will again climb upwardly under centrifugal force and discharge itself onto the shoulders 33.

At its lower end, the interior of the tube 11' is open to the outside air which 20 passes upwardly (which interior is within the spindle) and around the standpipe 24. The upward tapering and flaring of the high speed rotary nozzle 16 creates sufficient draft to insure a considerable flow of air within 25 the spindle. This stream of air passes through the annular space between the thimble 35 and the standpipe cap 29, whence it is discharged into the nozzle 16. If this entire stream of air were forced downwardly and 30 outwardly around the lower periphery of the cap, it would not only be materially restricted in its free passage, but would tend, because of its velocity, to disrupt the continuous feed of oil from the discharge surface 31 of the 35 cap onto the nozzle. To avoid these effects, I provide a plurality of vertical holes 38 through the head 29 directly over the end of the thimble 35, so that the air carried up within the spindle 11 and the thimble 35 will continue its upward flow without restriction or 40 deviation. As shown in Figure 3, these vertical holes are arranged in pairs between the three radial feed ducts 29', whereby the fuel oil is in effect fed across the air stream but 45 without actual contact therewith. Since the major portion of the air flow is through the holes 38, there is but little interference by the air stream with the oil feed from the stationary cap onto the rotary nozzle.

50 Even after the oil has been emptied from the bottom of the pocket 37, the centrifugal force of the air set in motion by the skin friction with the rotary outer wall of the pocket will tend to climb the tapering wall and exert 55 a slight upward pressure against the oil being transferred across the gap from the stationary discharge surface 31 to the nozzle shoulder 33. This force tends to prevent any oil not readily passed across the gap from gravitating down into the pocket. The centrifugally developed air pressure is also somewhat augmented by the higher air pressure developed in the pocket which is higher than that immediately above the pocket, due to the 60 fact that the total of the areas of the air pas-

sages 38 is somewhat less than the area of the annular air passage between the standpipe and the nipple.

The upper end of the nozzle 16 is open, and better results are obtained if it is not shielded. 70 This leaves the lower end of the nozzle, as well as the standpipe cap 29, exposed to the intense heat within the fire box. The previously discussed carbon formations which tend to accompany exposure to such heat are 75 prevented on the inner surfaces of the nozzle by the moving oil film and the cooling air carried up through the spindle 11. By carrying the oil fed up through the standpipe and its radial ducts 29', the oil serves as a cooling 80 medium to absorb heat from the exposed surfaces of the cap, and hence keep the cap below the temperature at which the troublesome carbon deposits will form. The heating of the oil also tends to make it thinner 85 and less susceptible to interruptions in its feed across the gap between the cap and the rotary nozzle 16. Leading the air stream through the holes 38 in the cap 29 likewise, and to a greater extent, cools the exposed surfaces of the cap. The holes 38 are long 90 enough to provide a considerable radiating area of the cap to the air passing therethrough.

While I find that three of the radial ducts 95 29' is the most satisfactory number, I contemplate that there may be more or less than these, and that even one duct may be made to suffice.

When a plurality of ducts 29' are used as in the present disclosure, one of the ducts is preferably drilled to communicate with the central bore of the head at a level very slightly lower than the others, so that at low rates of consumption per hour the small flow 100 of oil will not have to be divided among a number of ducts, but may be concentrated in a single duct to facilitate the continuity of oil delivery.

Since the cap 29 is ten or twelve inches 105 from the fixed base of the standpipe and there is a clearance of only 1/64 of an inch between the cylindrical discharge surface 31 and the upper end of the spindle 16, the head obviously cannot be moved sufficiently to 110 "sp. ing" it permanently out of alignment. When a poker or similar tool is inserted through the mouth of the rotating nozzle and down into the throat to scrape carbon deposits therefrom, the poker is very apt to hit 115 the cap. The poker, however, can move my cap only 1/64 of an inch when the cap will contact the rotating spindle. As soon as the poker is removed the cap springs back to its 120 central position.

125 In Figures 4 and 5 I have shown a modification of the standpipe head. In this form the radial ducts 29'' lead onto a conical distributing and discharge surface in the form of an apron 39'. The air passages instead 130

of being vertical holes through the head are vertical slots 38' through the apron. The apron as shown in Figure 5 is thereby divided into six sectors, the radial ducts 29' leading the oil onto alternate sectors. In this modification, the knife edge of the apron may be opposite the upper interior surface of the spindle 11 as in the construction of Figures 2 and 3, or as indicated by the broken lines in Figure 4, the apron may discharge the oil directly onto the lower interior wall of the nozzle 16 above the shoulder 33. A squared protuberance 40 at the top of the standpipe 24 may be employed for engagement by a suitable socket wrench to unscrew the cap from the standpipe. In the form shown in Figures 2 and 3, a suitable spanner wrench may be employed to engage two of the air passage holes 38.

In Figures 6 and 7, I have shown a still further modification of the standpipe cap. It differs from that in Figures 4 and 5 in that instead of leading the oil onto the apron through radial ducts, the oil is passed through a central aperture 40' at the top of the cap and allowed to flow over the top surface of the cap and over the apron 39" in a film. The apron 39" is provided with air passage holes 38" similar to the holes or slots 38' of the cap of Figures 4 and 5. In the cap of Figures 6 and 7, the oil is discharged from the margins of all of the apron sectors formed by the holes or slots 38". Since there is a continuous flow of oil over all the entire upper surface of the cap exposed to the intense heat of the flames, the surface is sufficiently cooled by the oil and the oil moves sufficiently fast to prevent the formation of carbon deposits. The apron 39" acts as a radiator to the air passing upwardly through the holes or slots 38" for helping to keep the upper surfaces of the cap cool. The central opening 40' may be of squared or hexagonal contour for the reception of a suitable wrench.

While I have described these particular embodiments of my invention, it is to be understood that many changes may be made therein without departing from the scope or spirit of the invention.

What I claim is:

- An oil burner comprising a head having a hollow spindle rotatably mounted therein, a tube supported in said hollow spindle and extending upwardly to a point adjacent the upper end of said spindle, a thimble having reduced ends mounted in the upper end of said spindle, one end of said thimble projecting downwardly into said tube, and the other end of said thimble forming an annular pocket between it and said spindle, a standpipe extending upwardly through said tube and said thimble and in spaced relation thereto to form an air passageway, said spindle extending upwardly into an outwardly flaring atomizing nozzle, and a tip for

said standpipe for leading oil therefrom over the end of said thimble to the inner surface of said spindle.

- An oil burner comprising a head having a hollow spindle rotatably mounted therein, a tube supported in said hollow spindle and extending upwardly to a point adjacent the upper end of said spindle, a thimble mounted in said spindle and projecting upwardly to form a pocket between said thimble and said spindle, a standpipe in spaced relation thereto to form an air passageway, an outwardly flaring tubular atomizing nozzle detachably mounted on said spindle, and a cap for the upper end of said standpipe having oil guiding means extending over the upper end of the thimble for carrying the oil across the stream of air flowing from said passageway and for supplying it to said nozzle.

- An oil burner comprising in combination a rotary tubular atomizing nozzle flaring upwardly and outwardly, a stationary standpipe for supplying oil thereto, a passage between the standpipe and nozzle for the flow of air through the nozzle and out its said flaring end, said standpipe having a tip provided with an annular oil leading member extending to a point closely horizontally opposite the inner surface of the nozzle for conducting oil from said standpipe outwardly horizontally across said air flow and discharging it directly and annularly onto said surface as a continuous annular stream.

- An oil burner comprising a rotary tubular atomizing nozzle, a standpipe disposed therewithin, means providing an air stream along the exterior of the standpipe and through the tubular nozzle, and a tip for the end of the standpipe having means thereon for discharging oil therefrom directly onto the inner surface of the rotary nozzle, said means comprising an annular distributing flange extending from the standpipe toward said inner surface of the nozzle, and passage means on the tip for carrying oil from the standpipe onto the flange across said air stream.

- An oil burner comprising a rotary nozzle having an inverted bell-shaped discharge opening, a stationary oil supply conduit extending to the interior of said nozzle, a tip for said conduit having an annular distributing surface extending outwardly from the tip closely to the inner wall of the nozzle and exposed to the heat at the mouth thereof, and passage means for carrying oil from the conduit onto the said exposed surface, said surface discharging oil horizontally aided by centrifugal force directly and in an uninterrupted continuous stream onto the inner surface of the nozzle.

- In an oil burner, the combination of a rotary tubular nozzle having an upwardly flaring inner surface, a standpipe leading

- upwardly to the interior of the nozzle, a passage for an air stream passing through said nozzle and discharged from said nozzle, a cap on the standpipe having an annular enlargement extending substantially to the inner surface of the nozzle, a passage in the head leading from the standpipe onto said surface for discharging oil thereon, said surface discharging the oil onto the nozzle, and 10 a plurality of air passages through the cap for carrying the air stream around the oil passing onto said surface.
7. In an oil burner, the combination of a rotary tubular nozzle having an upwardly flaring inner surface, a standpipe leading upwardly to the interior of the nozzle, a passage between the standpipe and the nozzle for a flow of air through the nozzle, a cap for the standpipe exposed to heat through the 20 mouth of the nozzle and having means for leading the oil from the standpipe to the nozzle, and passages for said air flow in the cap forming radiating surfaces for cooling the cap.
- 25 8. An oil burner comprising a rotary hollow atomizing nozzle outwardly flared at its upper end to discharge oil therefrom centrifugally, a standpipe extending into the interior of said nozzle, and a head for said 30 standpipe having an annular external oil delivering surface, the opposite surface of the nozzle being closely spaced transversely therefrom to draw oil outwardly directly from the head onto the inner surface of the 35 atomizer.
9. An oil burner comprising a vertical oil delivering feed pipe, a tubular rotary atomizing nozzle disposed about the standpipe and outwardly flared at its upper end for centrifugally discharging oil, and means for delivering oil from the feed pipe to the nozzle in a uniform flow comprising a tip on the standpipe having a continuous external cylindrical delivering surface, oil passage means 40 45 from the feed pipe to said surface, and a continuous internal cylindrical surface on the nozzle horizontally opposite said surface of the tip and closely spaced therefrom to permit the direct passage of oil, and an upwardly 50 facing shoulder on the nozzle at the upper edge of its said surface and within the vertical margins of said surface of the tip for drawing oil away from said surface of the tip by centrifugal force.
- 55 10. An oil burner comprising a vertical oil delivering feed pipe, a tubular rotary atomizing nozzle disposed about the standpipe and outwardly flared at its upper end for centrifugally discharging oil, and means for delivering oil from the feed pipe to the nozzle in a uniform flow comprising a tip on the standpipe having a continuous external cylindrical delivering surface, oil passage means 60 65 from the feed pipe to said surface, and a continuous internal cylindrical surface on the
- nozzle horizontally opposite said surface of the tip and closely spaced therefrom to permit the direct passage of oil, and a well carried by the nozzle beneath said surfaces, said well having an upwardly and outwardly tapering wall for carrying such oil upwardly by centrifugal force and discharging it between said surfaces. 70
11. An oil burner comprising a vertical oil delivering feed pipe, a tubular rotary atomizing nozzle disposed about the standpipe and outwardly flared at its upper end for centrifugally discharging oil, and means for delivering oil from the feed pipe to the nozzle in a uniform flow comprising a tip on the standpipe having a continuous external cylindrical delivering surface, oil passage means from the feed pipe to said surface, and a continuous internal cylindrical surface on the nozzle horizontally opposite said surface of the tip and closely spaced therefrom to permit the direct passage of oil, and means for providing an upward flow of air between said surfaces for preventing oil from falling downwardly from between said surfaces. 75 80 85
12. A fuel oil burner comprising a vertically disposed hollow rotary atomizing nozzle outwardly flared at its upper end to discharge oil centrifugally, a fuel feed pipe extending into the interior of the nozzle, and a tip on the pipe having a cylindrically conformed external surface constituting a stationary oil delivering surface onto which oil passes from the standpipe, the inner surface of the rotary 90 95 100 nozzle horizontally opposite said delivering surface being closely spaced therefrom to draw oil aided by centrifugal force directly from said delivering surface in a continuous horizontal stream. 105
13. A fuel oil burner comprising a vertically disposed hollow rotary atomizing nozzle outwardly flared at its upper end to discharge oil centrifugally, a fuel feed pipe extending into the interior of the nozzle, a tip on the pipe having a cylindrically conformed external surface constituting a stationary oil delivering surface onto which oil passes from the standpipe, the surface of the rotary nozzle horizontally opposite said delivering surface being closely spaced therefrom to receive oil directly from said delivering surface, and means for passing an air stream upwardly through the nozzle comprising passageways through the tip within its said oil delivering surface whereby the air stream does not impede the uniform feed of oil between said surfaces. 110 115
14. An oil burner comprising in combination an outwardly tapered rotary atomizing nozzle, a stationary oil feed conduit extending into the throat of said nozzle, the conduit having an annular oil delivering surface in close proximity to the inner surface of the throat of the nozzle forming an air gap of 120 125 130

capillary dimension for delivering oil thereonto horizontally across said gap by the aid of cohesion and centrifugal force, and an air passageway within the circumference of said surfaces for permitting the flow of air into the throat of the nozzle.

15. An oil burner comprising in combination a rotary atomizing nozzle, a slightly resilient oil feeding standpipe rigidly fixed at 10 one end and extending into and terminating within said nozzle, means affording an upward air passage to the atomizer between the nozzle and standpipe, opposed cylindrical surfaces on the free end of the conduit and 15 on the nozzle for transferring oil by the aid of cohesion and centrifugal force from the standpipe onto the rotary nozzle and across said air passage, the space between said surfaces being of capillary dimension so that 20 the nozzle will limit the transverse movement of the free end of the standpipe within the limits of the inherent resiliency of the standpipe.

16. The combination with an oil burner 25 apparatus, of a rotary atomizing nozzle having an upwardly flared bore, a liquid fuel standpipe disposed within the bore, an air passage between the standpipe and the nozzle, a fuel distributing head on the standpipe 30 for delivering fuel onto the inner surface of the nozzle, and an air passage through the head for the air flowing from the first passage to cool the head.

17. An oil burner comprising a vertical oil 35 feed stand pipe, a tubular rotary atomizing nozzle disposed about the standpipe and outwardly flared at its upper end for centrifugally discharging oil, and means for delivering oil from the feed pipe to the nozzle in a 40 uniform flow comprising a tip on the standpipe having a continuous external cylindrical delivering surface, oil passage means from the feed pipe to said surface, and a continuous internal cylindrical surface on the nozzle 45 horizontally opposite said surface of the tip and closely spaced therefrom to permit the direct passage of oil, and an upwardly facing shoulder on the nozzle at the upper edge of said internal cylindrical surface for drawing 50 oil away from said surface of the tip by centrifugal force.

18. An oil burner comprising in combination a rotary tubular atomizing nozzle-flaring upwardly and outwardly, a standpipe for 55 supplying liquid fuel thereto, and extending into the throat of the nozzle leaving a passageway between the standpipe and nozzle for the upward flow of air through the nozzle and out its said flaring end, a fuel distributing 60 head on the standpipe provided with an annular oil discharging head extending closely to the inner surface of the nozzle for conducting fuel oil from the standpipe directly and annularly onto said nozzle surface as a 65 continuous annular stream, and passage

means for conducting said upwardly flowing air past the plane of said liquid fuel feed but precluding the contact of the fuel with the air traversing said passage means in the head.

19. In combination with an upwardly and outwardly flaring rotary tubular atomizing nozzle, of means for delivering fuel oil from a relatively stationary standpipe onto the inner surface of the nozzle into the throat of which the standpipe extends, said nozzle having a vertical cylindrical inner wall portion, a distributing head carried by the standpipe and provided with a vertical cylindrical discharge periphery horizontally opposite said cylindrical surface of the nozzle and means for conducting liquid fuel from the standpipe to the discharge periphery, the annular space between the said discharge periphery of the standpipe and said cylindrical surface of the nozzle being so small as to permit the direct flow of fuel oil from the one to the other in an annular continuous stream which bridges said space against the force of gravity. 75

20. A liquid fuel burner comprising in combination a vertically mounted upwardly and outwardly flaring rotary tubular atomizing nozzle, a vertical standpipe extending into the throat of the atomizer and forming a conduit for the delivery of liquid fuel to the burner, and a distributing cap carried on the standpipe within the throat of the nozzle and provided with a peripheral fuel discharge surface, said nozzle having an annular vertical walled receiving surface portion in its throat horizontally opposite said discharge surface of the cap, and means for conducting liquid fuel from the conduit of the standpipe downwardly onto said discharging surface, said surfaces being so closely spaced that the liquid fuel is delivered in a continuous, uninterrupted stream across the gap between said surfaces and against the force of gravity. 100

21. The combination in a fuel oil burner 110 of a vertically mounted rotary tubular atomizing nozzle having a throat at its lower end and extending upwardly with an outward flare to form an inverted centrifugal atomizing bell for liquid fuel delivered to the inner wall of its throat, and a relatively stationary vertical standpipe extending upwardly into the throat of the nozzle, of means for delivering liquid fuel from the standpipe onto the inner surface of the atomizer 120 at its throat, comprising an annular vertical receiving surface portion in the throat of the atomizer and a distributing cap carried by the standpipe and provided with a fuel oil discharge surface closely spaced from and horizontally opposite said receiving surface of the atomizer, and means for delivering liquid fuel from the standpipe to said discharge surface, the said two surfaces being 125 so closely spaced that the liquid fuel is carried 130

ried from the said stationary surface of the standpipe cap to said rotary receiving surface of the atomizer under substantially no radial momentum and against the action of gravity and directly from one surface to the other in a continuous flow.

22. In an oil burner the combination of a vertically mounted rotary tubular upwardly and outwardly flaring atomizing nozzle for liquid fuel having an annular inner surface, a stationary standpipe extending into the throat of the nozzle for delivering liquid fuel thereto, there being an annular vertical gap between the standpipe and nozzle, said gap being of such dimension that the liquid fuel is passed directly and horizontally from the stationary standpipe across said vertical gap onto the inner surface of the atomizer.

23. In an oil burner the combination of a vertically mounted inverted bell shaped rotary nozzle for liquid fuel, a stationary standpipe extending into the interior of the nozzle for delivering liquid fuel thereto, an oil delivering surface on the standpipe extending toward the inner surface of the nozzle and forming a vertical open space therebetween, said space being of such size that the liquid is transferred from said stationary standpipe to the inner surface of said rotary nozzle directly and horizontally across said open space, opposed to the force of gravitation.

24. An oil burner comprising a rotary spindle, a tubular atomizing nozzle thereon, a standpipe projecting upwardly through the end of said atomizing nozzle, a thimble carried by the spindle surrounding the standpipe and having an annular portion inwardly spaced from the atomizer and projecting upwardly thereinto, and means supported by said standpipe for delivering the oil flowing therefrom onto said atomizing nozzle at a level substantially that of the top of said thimble.

25. Means for delivering fuel oil onto the interior surface of a rotary upwardly and outwardly flaring tubular atomizer nozzle from a stationary standpipe disposed therewithin, comprising, in combination therewith, a cap for the standpipe having an annular oil leading member extending to a point closely horizontally opposite said inner surface of the nozzle and forming therewith an annular gap, said oil leading member providing a path for conducting oil from the standpipe and outwardly discharging it horizontally across said gap directly onto said surface in a continuous annular stream.

26. In an oil burner the combination of a rotary nozzle for liquid fuel, a stationary standpipe extending into the interior of the nozzle for delivering liquid fuel thereto, an oil delivering surface on the standpipe extending toward the inner surface of the nozzle and forming a vertical open space therebetween, said space being of such size that

the liquid is transferred from said stationary standpipe to the inner surface of said rotary nozzle directly and horizontally across said open space, opposed to the force of gravitation.

In witness whereof, I hereunto subscribe my name this 8th day of November, 1924.

FRANKLIN HARDINGE.
